(57) The ornamental design for a animal paws scarf, as shown and described.

DESCRIPTION

FIG. 1 is a top plan view of a animal paws scarf showing my design;

FIG. 2 is a bottom plan view thereof;

FIG. 3 is a right side-elevation view thereof;

FIG. 4 is a left side-elevation view thereof;

FIG. 5 is an enlarged front elevation view thereof; and,

FIG. 6 is an enlarged rear elevation view thereof.
